ELECTRIC COUNTER TOP COOKING RANGE

Philip H. Peters, Jr., Washington County, and John L. Matrone, Albany County, N.Y., assignors to Environment/One Corporation, Schenectady, N.Y.

Filed Sept. 23, 1971, Ser. No. 183,288

Term of patent 14 years

Int. Cls. D7—02; D6—04

U.S. Cl. D7—111

FIG. 2

FIG. 3

FIG. 1 is a front perspective view of an electric counter top cooking range showing our new design;

FIG. 2 is a top plan view thereof;

FIG. 3 is a front elevational view thereof;

FIGS. 4 and 5 are rear and side elevational views thereof, respectively.

The characteristic features of the design resides in the smooth top surface appearance of the electric counter top cooking range together with associated control knobs and dials on the front edge portion and cooking site identification marks on the smooth top surface.

We claim:

The ornamental design for an electric counter top cooking range, as shown and described.
